[57] CLAIM

The ornamental design for a container for first aid items or the like, as shown and described.

DESCRIPTION

FIG. 1 is a top isometric view of a container for first aid items or the like showing my new design;

FIG. 2 is a bottom isometric view showing the rear and end not seen in FIG. 1; and

FIG. 3 is an isometric view of the separated top and bottom portions thereof.
